UNITED STATES PATENT OFFICE.

OSCAR M. LEICH, OF GENOA, ILLINOIS, ASSIGNEE TO LEICH ELECTRIC COMPANY, OF GENOA, ILLINOIS.

RECTIFIER.

1,366,395.

Specification of Letters Patent. Patented Jan. 25, 1921.

Application filed March 24, 1919. Serial No. 284,523.

To all whom it may concern:

Be it known that I, OSCAR M. LEICH, a citizen of the United States, residing at Genoa, in the county of Dekalb and State 5 of Illinois, have invented a certain new and useful Improvement in Rectifiers, of which the following is a full, clear, concise, and exact description, reference being had to the accompanying drawings, forming a part of 10 this specification.

My invention relates to converters, pole changers or rectifiers, and more particularly to vibratory machines of the above type. My invention has for its object the provision 15 of an improved structure for the contact elements of such devices. Machines of the above types are utilized to change alternating current to uni-directional current, uni-directional current to alternating current, to 20 vary the frequency and for other purposes when it is necessary to modify the character of the current. Devices of this character have a vibratory element which carries a contact or contacts, which vibratory element 25 is frequently called upon to vibrate at a relatively high frequency. The vibratory element controls the change in the current conditions between the entering and leaving current and it is of the utmost importance 30 that the operations of this vibrator element be uniform and that the contact durations be uniform. Difficulties have generally been experienced with devices of this character due to a non-uniform operation, due to burning 35 out of the contacts and due to an unsatisfactory modification of the current.

It is the prime object of my invention to so arrange the contact portions of devices of this character that the danger of burning 40 the contacts due to non-uniform operation is practically, if not entirely, avoided; further, that the duration of the contact be uniform and in fact that the entire operations of the device be of such a character as 45 to insure uniformity of operation.

I will describe a form which my invention may take more in detail by referring to the accompanying drawing, in which—

Figure 1 is a front view of a converter

constructed in accordance with my invention; 50

Fig. 2 is a sectional view on line 2—2 of Fig. 1, and

Fig. 3 is a view somewhat diagrammatic illustrating one form of circuit arrangement 55 in which my improved device finds application.

My improved device as herein illustrated is mounted upon a suitable bracket 10, which bracket supports the two electromagnets 11, 12. The bracket also carries arms 13 and 14, which arms are insulated from the bracket and carry stationary contact elements 15 and 16. These contact elements are mounted upon screw threaded bolts 17 60 which coöperate with nuts 18 so that these contacts 15 and 16 may be permanently adjusted into any desired position. The bracket 10 also supports a permanent magnet 19 which coöperates with the electromagnets to polarize the armature 20 of the device. This armature is suitably held between the fingers 21 and 22 of the non-magnetic plate 23. The plate 23 is adjustably secured in position upon the extremities 70 of the pole pieces 24 of the electromagnets 11 and 12. The armature 20 coöperates with these protruding pole pieces. The armature, as stated, is pivotally mounted and carries an arm 25, which arm is secured 80 to the protruding stem 26 of said armature by the set screw 27. The arm carries at its lower extremity a substantially U-shaped element consisting of the coöperating parts 28 which are mounted on opposite sides of 85 a distance piece 29 fixedly secured to the arm 25. The U-shaped element supports a contact carrying structure 30 U-shaped in form, this structure being rigidly secured at its extremities to the U-shaped structure 28 90 by the screws 31 and 32 respectively. The screws 32 at the same time serve to carry suitable weights 33 which it is desirable to use in connection with the vibratory portion of the device. The U-shaped contact carrier 30 bulges outwardly slightly below the weights 33, as more clearly seen from an inspection of Fig. 1, and carries contacts 34 at 95

its lower portion, which lower portion is not backed by the elements 28. There is thus a certain yielding from side to side of said element 30 relatively to the remaining portions of the vibratory part of the device. The element 30 however is rigid enough so that for practical purposes the contacts 34 remain relatively to each other in the same position. The contacts 34 are both in electrical connection with the element 30 and co-operate respectively with the co-operating stationary contact elements 15 and 16. It will be noted that the sum of the two air gaps by virtue of this construction is maintained constant by reason of the fact that the distance between the two contacts 34 always remains substantially the same. There is, however, a yielding when necessary, but in such a case the yielding takes place relatively between the elements 30 and 28. Thus, if the contact 34 has touched the contact 15 of the vibratory portion, and the device then moves farther to the right, such movement does not increase the air gap between the contact 34 and the contact 16.

I find it of considerable importance to have the two contacts 15 and 16 quite a considerable distance apart for practical purposes, thus making it of the utmost importance to have the separated contacts 34. It will also be noted that by virtue of this construction the pressure against contact 15 will be the same as the pressure against contact 16 as the pressure is due to the combined yielding of both arms of the element 30. This is of great importance in order to get uniform contact pressure.

Referring more particularly to Fig. 3, I show my improved device as applied to a system for rectifying the current from an A. C. source 35 so as to charge a storage battery 36. The alternating current is led through the primary 37 of a transformer and current is also supplied from this source to the electromagnets 11 and 12 through the agency of the conductors 38 and 39, a condenser 40 being interposed. The secondary winding 41 of the transformer is by virtue of the conductors 42 and 43 connected respectively to the contacts 15 and 16. One terminal of the storage battery is connected by means of conductor 45 with the vibratory element of the device which includes the contacts 34. This circuit arrangement is merely shown for illustrative purposes to indicate one manner of use to which my device may be put. The vibratory element vibrates in accordance with the alternations of the current from the alternating current source so that a uni-directional current flows through the storage battery 36, as will be readily understood by those skilled in the art.

Although I am unable to state definitely the theory or reason why the form of struc-

ture herein accomplishes the result stated and while the reasons hereinbefore outlined may or may not be the correct ones, yet I believe that one reason why the structure solves the problem is due to the use of two springs, independently mounted, which together carry the contact or contacts. One spring alone may have a tendency to vibrate on its own account, whereas two independently mounted springs tied together at their free ends would not have such tendency because of their different rates of vibration.

From the description thus given of my improved device, its mode of operation will be readily apparent. I claim, however, not only this particular structure but all forms and modifications thereof which are within the scope of the appended claims:

1. A vibratory converter of the character described having a pair of relatively stationary contacts, a pair of movable contacts spaced apart and co-operating with said stationary contacts, a vibratory element, and a U-shaped framework carrying said movable contacts yieldably mounted upon said vibratory element.

2. A vibratory converter of the character described having a pair of relatively stationary contacts, a pair of movable contacts spaced apart and co-operating with said stationary contacts, a vibratory element, and a U-shaped framework carrying said movable contacts mounted upon said vibratory element.

3. A device of the character described having a relatively stationary contact, a vibratory element including a substantially rectangular framework with yielding sides, and a contact co-operating with said first contact carried by one of said sides.

4. A device of the character described comprising a vibratory element including a substantially rectangular framework with yielding sides, contacts mounted upon said yielding sides, a pair of relatively stationary contacts co-operating with the aforesaid contacts, and a framework for supporting said stationary contacts upon opposite sides of said framework.

5. A device of the character described comprising a pair of relatively stationary contacts, a pair of yieldingly carried movable contacts spaced apart and co-operating each to each with said stationary contacts, and means for supporting said yieldingly carried contacts consisting of two arms made of resilient material secured together at their extremities.

6. A device of the character described comprising a pair of relatively stationary contacts, a pair of yieldingly carried movable contacts spaced apart and co-operating each to each with said stationary contacts, and means for supporting said yieldingly carried contacts consisting of two arms

made of resilient material secured together at their extremities, the said contacts being mounted upon said arms near one extremity thereof.

5 7. A device of the character described comprising a relatively stationary contact, a movable contact, and two springs spaced apart, on one of which said movable con-

tact is mounted, said springs at one extremity thereof being substantially rigidly 10 mounted and having their other extremities fastened together.

In witness whereof, I hereunto subscribe my name this 11th day of March, A. D., 1919.

OSCAR M. LEICH.
